FREDERICK BERNARD DÆRING, OF LONDON, ENGLAND.

Letters Patent No. 72,465, dated December 24, 1867; patented in England, September 4, 1867.

IMPROVED MACHINE FOR BORING ROCKS.

The Schedule referred to in these Letters Patent and making part of the same.

TO ALL WHOM IT MAY CONCERN:

Be it known that I, FREDERICK BERNARD DÆRING, of London, England, civil engineer, have invented or discovered certain "Improvements in Engines or Machinery for Boring or Working in Rock or other Mineral;" and I do hereby declare that the following is a full, true, and exact description thereof, reference being had to the annexed drawings; that is to say—

My invention mainly consists in employing the main cylinder of the engine as a distributor of the compressed air or other motive-fluid to the valve-cylinder, and other small cylinders used in connection therewith, the motive-fluid not having been previously utilized in the main cylinder.

Figures 1 and 1 are longitudinal sections, showing the piston at the two ends of its stroke.
Figure 2, a section through X X, fig. 1.

Figures 3 and 4 are top and bottom plans, and

Figure 5 a rear elevation of an engine constructed according to the principles of my invention. The main cylinder, A, in addition to its ordinary ports for admitting the fluid for producing the forward and back strokes of the piston, has two ports, *f* *d*, in communication, respectively, through pipes *f'* *d'*, with the back of the valve of the cylinder, and with the back of a cylinder, P, of the advance movement. The main cylinder has also a central main supply-port, *l*, in constant communication with the fluid-supply. The piston-rod carries three pistons, *a* *b* *c*, forming between them two chambers. The forward chamber communicates with the outer air by a passage, *e*. The hindmost chamber always carries compressed air.

A constant pressure is maintained against the forward end of the valve, the rod of which carries four pistons, the two outer pistons forming the valve-piston proper, while the others are piston-valves, and close and open at the proper times the ports leading to the main piston. The forward valve-piston is of smaller area than its back piston. A constant pressure is likewise maintained at the front of the advance-movement cylinder P, fluid communicating this pressure being supplied through pipe *k* *k*. As the main piston is making its forward stroke, the port *f* is put into communication through the back chamber of the main piston with the main supply-port *l*. The fluid thus flows to the back of the valve-cylinder, where, acting upon a greater area than is acted upon by the constant pressure at the front, it moves the valve forward. This puts the main supply *l* in communication with the front of the main cylinder, through the port and side pipe *h*, so that the main piston is caused to make its back stroke. In the stroke it cuts off the port *f*. The chamber at the back of the valve-cylinder then exhausts through the pipe *f'*, port *f*, and the passage *e*, so that the constant pressure on the front piston of the valve-rod, not being resisted, moves the valve back to open the port leading to the back of the main piston, and so on. In both strokes the main exhaust is through the valve-casing at *i*. The piston of the advance cylinder P is kept at the front by pressure exerted at the back, which is of larger area than the front. In the forward stroke of the main piston, the port *d* is passed by the main piston only when the tool has cut to a determined depth, and the piston of the advance cylinder is therefore kept at the front until the main piston is able to make its full stroke; when exhaust takes place through the pipe *d'*, the port *d*, and the main cylinder, and its exhaust-passages. The constant pressure on the front of the piston then drives the piston back and withdraws the pawl carried by the piston from its ratchet-wheel, ready to rotate this wheel and advance the engine at the next stroke of the main piston. In some cases I reverse the valve of the engine before explained; that is to say, I place the small piston at the back instead of at the front of the valve. The main exhaust at *i* then takes the place of the main supply at *l*, and *vice versa*. A hole in the back cover of the valve may then be used to regulate the speed of the valve, an excess of constant pressure in the forward cylinder, instead of being placed so that it is behind the piston after the completion of a full stroke, may be placed so that it is behind the middle partition of the piston. The advance piston is in this case moved by pressure at the end of the forward stroke.

A modification of the arrangement before described, and in which also the main cylinder acts as a distributor of the motive-fluid without previously utilizing it, consists in fitting the main piston-rod with four pistons, forming between them three chambers. In this case it is not necessary to maintain a constant pressure against one side of the valve-piston or against one side of the small piston or pistons. The centre chamber forms

the distributor, and the two outer chambers form the exhaust-chambers for the other cylinders. The foremost chamber communicates with the outer air through the piston-rod, as in the first arrangement, while the hindmost chamber communicates with the foremost chamber, and therefore with the outer air, by a pipe or passage carried through the two middle pistons. The main cylinder, in this case, has, in addition to the ordinary ports, four ports, viz, the first in communication with the back of the advance cylinder, and with the front of the valve-cylinder, the second for admitting the fluid between the two middle pistons, the third in communication with the back of the valve-cylinder, and the fourth in communication with the front of the advance cylinder. I do not, however, limit myself to any number of ports, because their number and partition will vary according to the number and required movements of the cylinders to be actuated therefrom, my invention consisting essentially in actuating the pistons of any cylinder used in connection with the main cylinder by employing the main cylinder itself as a distributor of the motive-fluid to the other cylinders, such motive-fluid not being previously utilized in the main cylinder.

I effect the required rotary motion of the piston and tool by means of a twisted, square, or cornered bar, *k*, or of a rod with a spiral feather or groove, in combination with other parts, as follows: The back part of the piston-rod is hollow, to receive the twisted rod, the rear end of which passes through the rear of the cylinder, and carries a ratchet-wheel, *m*. The twisted rod is a fixture, longitudinally, but is free to turn on its axis in one direction, while a pawl, *n*, which takes into the ratchet-wheel, prevents it turning in the other direction. In the back stroke of the piston the twisted rod is held by the pawl, and the piston-rod, which is formed internally to fit the bar, follows the twist, and is caused to rotate. In the forward stroke, the twisted rod being free to rotate, and being more easily rotated than the piston, the latter makes its stroke without rotating, while the twisted rod moves round the pawl, riding over the ratchet-tooth, or the piston may be made to rotate in the forward, and the bar in the back stroke, the alteration being effected by reversing the twist.

What I claim as my invention, and desire to secure by Letters Patent, is—

1. Constructing engines or machinery for boring or working in rock or other mineral in which the pistons of the small cylinders are operated by motive-fluid, distributed by the main cylinder, without having been previously utilized in the main cylinder, as herein described.

2. Constructing engines or machinery for boring or working in rocks or other mineral in which the main cylinder itself distributes the motive-fluid at distinct portions of the stroke to other cylinders, as in the arrangements herein described.

3. Constructing engines or machinery for boring or working in rock or other mineral in which the piston of the main cylinder, with the tool, has the required rotary motion imparted to it by a twisted bar, or equivalent, in combination with other parts, as herein described.

In witness whereof, I, the said FREDERICK BERNARD DÆRING, have hereunto set my hand, this tenth day of October, one thousand eight hundred and sixty-seven.

F. B. DÆRING.
